US00D729909S

(12) **United States Design Patent**
Castrigno et al.

(10) **Patent No.:** **US D729,909 S**
(45) **Date of Patent:** **** May 19, 2015**

(54) **ELBOW FITTING**

(71) Applicant: **Watts Water Technologies, Inc.**, North Andover, MA (US)

(72) Inventors: **Steven Castrigno**, Manchester, NH (US); **Jeffrey A. Scilingo**, Londonderry, NH (US)

(73) Assignee: **Watts Water Technologies, Inc.**, North Andover, MA (US)

(**) Term: **14 Years**

(21) Appl. No.: **29/453,624**

(22) Filed: **May 1, 2013**

(51) LOC (10) Cl. **23-01**

(52) U.S. Cl.

USPC **D23/263**

(58) **Field of Classification Search**

(57) **CLAIM**

The ornamental design for an elbow fitting, as shown and described.

DESCRIPTION

FIG. 1 is a perspective view of an elbow fitting according to the present disclosure.

FIG. 2 is a top view of the elbow fitting according to the present disclosure.

FIG. 3 is a bottom view of the elbow fitting according to the present disclosure.

FIG. 4 is a side view of the elbow fitting according to the present disclosure.

FIG. 5 is another end view, opposite to that of FIG. 4, of the elbow fitting according to the present disclosure.

FIG. 6 is another end view of the elbow fitting according to the present disclosure; and,

FIG. 7 is a side view, opposite to that of FIG. 6, of the elbow fitting according to the present disclosure.

The broken lines are shown for the purposes of illustrating portions of the elbow fitting and form no part of the claimed design.

1 Claim, 4 Drawing Sheets
